SUPPORTING FRAME FOR COLLAPSIBLE LUGGAGE

Harry E. Einhorn, Brooklyn, N. Y., assignor to Wilco Metal Products, Inc., New York, N. Y., a corporation of New York

Application November 15, 1954, Serial No. 468,592

4 Claims. (Cl. 190—43)

This invention relates to containers and has more particular application to valises, handbags and luggage.

An object of the invention is to provide a collapsible frame for supporting a pliant or flexible casing of the aforesaid containers in either a collapsed or an expanded condition.

Another object of the present invention is to provide a frame for a collapsible bag in which the frame may be enclosed in the bag and manipulated to and from expanded and collapsed conditions from without the bag.

A further object is to provide a collapsible bag frame which is simple in construction, easily manipulated between collapsed and expanded conditions, and one which will enable the bag to be folded into a small, compact bundle convenient for carrying, or for storage.

Other and further objects of my invention reside in the structures and arrangements hereinafter more fully described with reference to the accompanying drawings in which:

Fig. 1 is a perspective view of the bag in the expanded condition constructed in accordance with the principles of the invention;

Fig. 2 is a perspective view of the bag in a collapsed condition;

Fig. 3 is a perspective view, showing the collapsible frame expanded;

Fig. 4 is a perspective view of the collapsible frame shown in Fig. 3, in a partially collapsed condition;

Fig. 5 is an expanded view taken along line 5—5 of Fig. 3.

Illustrated in the figures of the drawing is a container in the form of a collapsible valise 10 which has an outer casing 12 of any suitable, flexible or pliant material. The valise 10 comprises both the outer flexible pliant material 12 and an inner supporting frame (not numbered) shown in greater detail in Figs. 3, 4 and 5. The frame permits the container or valise 10 to collapse into the condition as shown in Fig. 2 or to hold it in its expanded condition shown in Fig. 1.

The specific details of the casing 12, apart from the frame therein, do not form a part of the inventive feature of the invention and accordingly may be constructed in any well known manner.

The frame (Figs. 3, 4 and 5) includes a top member 14, a bottom member 16 and side walls 18 and 20. The top member 14 is of a rigid construction and when placed within the pliant casing material 12 lies adjacent to the top wall of the container. Similarly, the bottom member 16 also being constructed of a rigid material, lies adjacent to the bottom wall of the casing 12. The sides 18 and 20 of the casing frame, being of wire construction, fit along the sides and in the corners of the casing 12. Both sides 18 and 20 are similar in construction and a detailed description of one will suffice for both.

Taking the side frame 18, it will be noted (Figs. 3 and 4) that the same is composed of an upper member generally identified by the numeral 22 and a lower member generally identified by the numeral 24. The two

2

members 22 and 24 are of wire which has a diameter sufficient to insure rigidity to the side frames 18 and 20 and yet permits lateral movement of the type and for a purpose which will be described. Each lower member 24 forms a substantially closed rectangle while each upper member 22 has a body portion 26 and two arms 28 extending therefrom. The arms 28 are formed with in-turned fingers 30 to provide pivots for the upper members to permit the upper members 22 to pivot relative to the lower members 24.

Fixed to opposite sides of each lower member 24 is a pair of latches 32. Each of the latches 32 being similar in construction, comprises a U-shaped bent wall portion 34, hereinafter known as a latch wall and a chamber 36. When the latches 32 are applied to the members 22 and 24 the latch walls 34 enclose a portion of each lower frame 24 and are held rigid and in fixed position relative thereto by securing plates 38 placed over the chambers 36 and the enclosed fingers 30 and member 24. Screws or rivets 40 then hold the plates 38 in position. In this way the latches 32 accommodate the fingers 30 of the arms 28 and the members 24 for relative pivoting movement in the chambers 36.

As noted previously the members 22 are formed of wire having sufficient rigidity, but of such a nature as to permit lateral movement of the arms 28 so that they may move laterally between the walls 34 to assume the position shown by the dot dash lines in Fig. 3. Transverse apertures 42 which are defined in the latches 32 between the end of the U-shaped wall 34 and the body of the latches 32 provide openings through which the arms 28 may move transversely relative to the latch walls 34 and completely out of engagement with the latches 32, see Fig. 4.

Thus, when the frame for the casing 12 is in the expanded position as shown in Fig. 3 the arms 28, because of their rigid construction, will resiliently move between the U-shaped walls 34, there to be latched and retained in the same manner as the sides of the lower member 24 are retained between the latch walls 34. However, when it is desired to release the latching engagement of the arms 28 with the latches 32, the arms are squeezed laterally toward each other to assume the dot dash position shown in Fig. 3 and in alignment with the transverse aperture 42. They are then moved transversely out of the respective apertures by pivoting about the fingers 30 mounted in the chambers 36. At this time the upper and lower members 22 and 24 may be collapsed and pivotally moved relative to each other about the latch members 32.

The top and bottom rigid members 14 and 16 respectively are pivoted relative to the upper and lower frame members 22 and 24 respectively. The top member 14 pivots about the body portions 26 of the upper frame members 22 by the hinges 44 while the bottom member 16 is similarly pivoted to the bottom side of the lower frame members by the hinges 46. In this way when the upper and lower frames 22 and 24 pivot relative to each other about the latch members 32, both the top and bottom members 14 and 16 will also pivot relative to the respective frame members 22 and 24 to which they are hinged.

During the pivoting movements described above to insure that the rigid members 14 and 16 will seat properly in height with respect to the frame members to which they are hinged, guide members 48 are secured on the upper and lower frames 22 and 24 respectively. The guide members 48 limit the movement of the top and bottom members 14 and 16 by moving with the frames to which they are secured and by touching and laying over a portion of the top and bottom members so as to limit and guide the height of their movement relative to their respective frames.

When the valise 10 is in its expanded condition (Fig. 1) and the supporting frame therefor is also expanded as shown in Fig. 3, the arms 28 of the upper members 22 will be retained and latched between the latch walls 34 and into alignment with the similarly disposed arms of the lower members 24. To collapse the valise it is merely necessary to squeeze the arms 28 inwardly toward each other, that is, laterally between the walls 34 until they assume the position identified by the dot dash lines, Fig. 3. At such time they will be in alignment with the transverse apertures 42.

By then pivoting the upper members 22 relative to the latches 32 about their fingers 30 positioned in the chambers 36, the upper and lower members 22 and 24 will collapse relative to each other. In turn, the valise 10 and its flexible casing 12 will assume the collapsed condition shown in Fig. 2.

To expand the valise 10 from the collapsed condition shown in Fig. 2 to that shown in Fig. 1 it is merely necessary that the top and bottom walls of the valise be separated. This in turn will separate the top and bottom members 14 and 16 of the valise frame. As the members 14 and 16 are separated the upper and lower members 22 and 24 will assume relative positions substantially similar to that shown in Fig. 4.

Continued separation of the top and bottom members will move the arms 28 so that their outer surfaces will engage and ride along a side of the transverse apertures 42 until they are moved into the apertures. At that time, due to their own resiliency, the arms 28 will automatically spread laterally from their dot dash position to one in which they fit between the walls 34, see Fig. 3, there to be latched in alignment with the lower members 24. Together the pairs of aligned members 22 and 24 will form the sides 18 and 20 of the valise frame.

While there have been shown and described and pointed out the fundamental novel features of the invention as applied to a preferred embodiment thereof, it will be understood that various omissions and substitutions and changes in the form and details of the device illustrated and in its operation may be made by those skilled in the art, without departing from the spirit of the invention. It is the intention, therefore, to be limited only as indicated by the scope of the claims appended hereto.

I claim:

1. In a collapsible device having a casing of flexible material, a frame to reinforce the walls of said casing in an expanded position comprising a top member, a bottom member, a pair of wire frames at each end of said members including a lower member and an upper member, a pair of latches rigid with opposite sides of one end of each of said lower members, each latch having a latch area and an aperture, each of said upper members having a body, arms extending from said body and a finger on each of said arms pivotally mounted on a respective one of said latches, hinge means connecting said top and bottom members at the ends thereof with said bodies and the opposite ends of said lower members respectively, and means on said bodies and said opposite ends cooperating with said top and bottom members to guide the top and bottom members into an expanded position relative to said upper and lower members respectively.

2. In a collapsible bag having a casing of flexible material and having top, bottom side and front walls, a frame to reinforce said casing in an expanded position comprising a top member adjacent said top wall, a bottom member adjacent said bottom wall, wire frames adjacent each of said side walls, said wire frames each including a lower member and an upper member, a pair of latches fixed on opposite sides of one end of each of said lower members, each of said latches having a latch area and an aperture adjacent thereto, said upper members each having a body, arms extending from the ends of the body and pivot fingers bent from the ends of said arms, each of said pivot fingers being pivotally mounted on a respective one of said latches for movement relative thereto, hinges interconnecting said bottom member with said lower members at the ends thereof opposite said one end, hinges interconnecting said top member with the bodies of said upper members, and means on said bodies and said opposite ends of said lower members cooperating with said top and bottom members respectively to guide said respective members into said expanded position.

3. In a collapsible frame for a container, a side, said side having upper and lower relatively swingable members and a pair of latches fixedly secured to one of said members and cooperating with said other member to releasably lock the upper and lower members relative to each other in one position of their relative movement, said other of said members being substantially U-shaped, the ends of the arms of the U being bent to extend coaxially, said arms being resiliently movable toward and away from each other, each of said bent ends being slidably and swingably engaged with one of said latches, said latches, each having a reentrantly bent keeper and a side opening adjacent the edge of the keeper through which the sides of said other member may move laterally and transversely.

4. A collapsible device for maintaining in extended relation a casing of flexible material, said device comprising two opposed foldable side frames, each said frame including a pair of relatively swingable members, respectively upper and lower, a pair of latch members, one on each edge of said lower member, for releasably locking said upper and lower members against said relative movement, said latch members each having a reentrantly bent keeper and having a transverse opening adjacent said latch keeper, means on each said latch member to support said upper and lower members for said relative movement, arms on said upper member laterally movable in said last-named means and behind said latch keeper, in which position said upper and lower members are latched against said relative movement, and movable transversely from behind said latch keepers through said transverse opening to be free to engage in said relative swinging movement.
